CLAIM

The ornamental design for a plug and socket combination, as shown and described.

DESCRIPTION

FIG. 1 is a front-left perspective view of a socket element of a plug and socket combination.

FIG. 2 is a front elevational view thereof.

FIG. 3 is a top plan view thereof.

FIG. 4 is a left-side elevational view thereof, the right-side being a mirror image.

FIG. 5 is a bottom plan view thereof.

FIG. 6 is a front-left perspective view of a plug element of a plug and socket combination.

FIG. 7 is a front elevational view thereof.

FIG. 8 is a top plan view thereof.

FIG. 9 is a right-side elevational view thereof, the left-side being a mirror image.

FIG. 10 is a bottom plan view thereof; and,

FIG. 11 is a bottom-right perspective view of a plug and socket combination.

The broken lines shown in the drawings are for the purpose of illustrating portions of the plug and socket combination that form no part of the claimed design. The broken lines showing the polisher elements in FIGS. 1-5 and 11 are for the purpose of illustrating environmental structure and form no part of the claimed design.
